UNITED STATES PATENT OFFICE.

ELBERT N. SIPPERLEY, OF WESTPORT, CONNECTICUT.

CURTAIN-LIGHT.

1,109,475.

Specification of Letters Patent.

Patented Sept. 1, 1914.

Application filed April 21, 1914. Serial No. 833,511.

To all whom it may concern:

Be it known that I, ELBERT N. SIPPERLEY, of Westport, in the county of Fairfield and State of Connecticut, have invented certain new and useful Improvements in Curtain-Lights; and I do hereby declare the following to be a full, clear, and exact description of the invention, such as will enable others skilled in the art to which it appertains to make and use the same.

The object of this invention is to provide simple and highly efficient means for securing lights in the sides or curtains of a vehicle top, tent or portable house, whereby such lights may readily be removed when the top or curtain or sidewalls are to be folded or rolled, thereby avoiding the danger of breaking the lights which are usually made of fragile material.

20 In the accompanying drawings Figure 1 is an elevation. Fig. 2 is an enlarged sectional view on line 2—2 Fig. 1. Fig 3 is a section on line 3—3 Fig. 1.

Referring to the drawings, 1 designates a 25 flexible curtain, such as is used in vehicle tops, sidewalls of tents, portable houses, etc. In this curtain, which may be of any suitable material, is formed an opening of any desired shape and which is usually closed 30 by a sheet 3 of transparent material, preferably celluloid. Heretofore such transparent materials have easily been broken or damaged by folding or rolling the curtains when their use is not required. According 35 to my invention, when the curtains are to be so folded or rolled the lights are removed. For this purpose the opening in the curtain is surrounded by a pocket 4, which is preferably composed of inner and outer 40 parallel walls extending from the curtain proper and between which the edges of the sheet are designed to fit. Preferably the pocket extends along the top and opposite ends of the opening, but not along the bottom thereof, since otherwise snow or water might collect in the bottom pocket. I avoid all difficulty in this respect by extending the sheet beneath the lower edge of the opening. In the sheet, along its edges, I form suitably 50 spaced apart holes with eyelets therein through which detachable fastening mem-

bers are designed to extend. The particular construction of the fasteners may be widely varied. I have shown such means as comprising ball-and-socket fasteners, the stud 55 of the ball 5 being secured to one of the walls and the socket 6 to the opposite wall. Each stud after being extended through a hole in the light is caused to engage its respective socket, and in this way the fastening means may readily be disengaged when it is desired to remove the sheet. Any suitable means may be employed for securing the lower edge of the celluloid sheet and I have conventionally indicated fasteners 7 for 60 this purpose.

In practice, the light sheet is inserted upwardly through the end pockets until its upper edge fits within the upper pocket, and the eyelets of the sheet register with the 70 fasteners, which, being inserted through such eyelets, securely hold and lock the sheet in place, and yet enable it to be easily removed. Changes may be made without departing 75 from my invention. Any suitable fastening means may be employed.

I claim as my invention:

1. A flexible curtain having an opening therein and spaced-apart inner and outer walls forming a pocket surrounding the top 80 and sides of said opening, a sheet of transparent material fitted at its edges in said pocket and having openings formed therein, and detachable fastening means extending through such openings. 85

2. A flexible curtain having an opening therein and spaced-apart inner and outer walls forming a pocket surrounding the top and sides of said opening, a sheet of transparent material fitted at its edges in said 90 pocket and having openings formed therein, the lower edge of said sheet extending beneath the lower edge of said opening on the outside of the top, and fastening means extending through said openings. 95

In testimony whereof, I have signed this specification in the presence of two subscribing witnesses.

ELBERT N. SIPPERLEY.
